F. G. Lafayette

United States Patent Office.

FRANCIS G. LAFAYETTE, OF MIDDLETOWN, OHIO.

Letters Patent No. 85,939, dated January 19, 1869.

IMPROVEMENT IN FLOORING-CLAMPS.

The Schedule referred to in these Letters Patent and making part of the same.

To all whom it may concern:

Be it known that I, FRANCIS G. LAFAYETTE, of Middletown, in Butler county, in the State of Ohio, have invented a new and useful Improvement in Flooring-Clamps; and I do hereby declare that the following is a full and exact description thereof, reference being had to the accompanying drawings, and to the letters of reference marked thereon.

Figure 1 represents a side view of my improved clamp, and

Figure 2 represents an edge view of the same.

The levers A B are connected together by the metal plates *a b*, which may be loosely riveted or bolted, to serve as a hinge, on which the levers work in opening and closing them.

The ends of levers A B are furnished with the grappling-irons *c d*, the shanks of which pass through the ends of the levers A B, and are secured by nuts *e*.

To strengthen the levers A B, where the shanks of the grappling-irons pass through them, bands of metal are secured upon them, as denoted at *f f*.

Toward the upper ends of the levers A B, the ends of the double lever C, which embrace the levers A B, are secured by a bolt to the lever A, which bolt serves as a hinge, upon which the double or bifurcated lever C will move, for the purpose hereinafter specified.

Lever C is provided with a pawl, *s*, which works into the teeth of the rack *g*, secured to the lever B, and a friction-roll, *h*, is interposed between the two branches of lever C, as represented in fig. 1.

D is a hinged claw-brace, having its upper end hinged by a metal loop, *i*, to the stanchion E, and the latter is securely fastened to the lever A, so as to form a firm support for brace D.

The bent spring K is secured at its ends by bolts, shown in dotted lines in fig. 1, to the levers A and B.

The metal plates *a b*, and the two branches, *x y*, of lever C, are provided at their ends with a series of two or more holes, to permit the levers A and B to be adjusted toward or from each other, so as to allow the grappling-irons *c d* to open with their levers, to take hold of a joist, whether two or three inches in thickness.

The clamp is represented in fig. 1 as being properly adjusted to suit the thickness of a two-inch joist, but when the adjustment is made to set the jaws and grappling-irons to grasp a joist of three inches in thickness, the gauge-block H will be placed between the spring K and lever A.

The metal plates *m n* are secured upon levers A B, as wear-irons, against which the flooring-boards will press when the clamp is in use.

The loose end of stanchion E is formed in the arc of a circle on its upper edge, and the pin *t* is inserted

above it in the lever B, to aid in supporting it against the pressure upon brace D when being used to force a flooring-board up to its place in the floor of a building.

The pin *u* in the lever B serves as a stop to prevent the lever C from being forced below a horizontal line.

The object of my invention is to furnish an efficient implement, capable of convenient and rapid use, to form close joints in the laying of floors in buildings.

To use my flooring-clamp, the workman will remove pawl *s* from rack *g*, and throw up the handle, with its lever C, and compress the upper ends of levers A B, thereby spreading apart the grappling-irons *c d*, so as to embrace a joist, upon which the floor is being laid; then the attendant or workman will force down the lever C, and the friction-roll *h*, working against the lever B, will cause the grappling-irons *c d* to take firmly hold of the joist. The pawl *s* will then take hold of the rack-teeth, and retain the clamp in position ready for operation.

The position of the clamp will be such as is represented in fig. 2, and that side to which the hinged claw-brace is attached is the rear side.

The flooring-board to be forced up, to be nailed to the joist, will be immediately in front of the levers A B, and its edge will be in contact with the wear-irons or plates *m n*, and thereupon the workman will grasp the upper ends of the levers A B, while standing upon the flooring-board to be forced into place, and will pull the levers A B toward him until the groove and tongue of the flooring-boards are pressed snugly together, to form a tight joint, and, at the same time, the hinged claw-brace, which rests with its claw astride the joist upon which the clamp rests, and this claw-brace securely retains the clamp in place, holding the flooring-board until nailed by the workman.

The functions of spring K are to retain the levers in their longitudinal relation to each other, and to draw the upper ends of the levers A B toward each other, when lever C is raised up to release the grappling-irons *c d* from their hold upon the joist.

Having fully described my invention,

What I claim, and desire to secure by Letters Patent, is—

The combination of levers A, B, and C, with stanchion E, adjustable plates and branches *a b*, *x y*, spring K, gauge-block H, grappling-irons *c d*, and claw-brace D, connected, arranged, and operating in the manner and for the purpose substantially as described.

In testimony whereof, I have hereunto set my hand, this 12th day of May, A. D. 1868.

F. G. LAFAYETTE.
